UNITED STATES PATENT OFFICE

2,477,084

THERAPEUTIC AND DIAGNOSTIC MACHINE

Irving Rehman, Los Angeles, Calif., assignor of
one-fourth to Elberta M. Arnold and one-
fourth to Edward W. Lowman, both of Corona,
Calif.

Application October 20, 1945, Serial No. 623,535

2 Claims. (Cl. 128—420)

1

This invention relates to therapeutic apparatus, and more especially to an electrical machine for producing a direct or galvanic current together with an associated condenser discharge current.

Electrical machines for producing direct or alternating currents for therapeutic treatments have been heretofore produced. However, such machines have been found to be unsatisfactory in several respects, particularly in being incapable of producing certain desirable currents. These objections as well as others have been overcome by the present invention which has been developed and perfected for the production of a direct or straight galvanic current of a purer nature than has been found possible to produce by machines as heretofore known, and less painful to the patient.

It is therefore an object of my invention to provide a therapeutic machine for the production of electrical currents of a true galvanic nature in association with a discharge current from a condenser, or separately therefrom.

Another object of the invention is to provide an electrical unit for producing desired and selected currents adapted to be applied directly to an affected nerve, muscle, or other part of the human body, without affecting other parts thereof.

Another object of the invention is to provide a therapeutic machine adapted both for testing the affected parts and the treatment thereof.

Another object of the invention is to provide a novel, compact, portable machine for producing a true galvanic current for the testing and treatment of nerves, muscles, and other parts of the human body and adapted for the superimposing of a discharge current from a variable condenser on the galvanic current, which superimposed condenser discharge current may be applied periodically or at selected time intervals.

Other objects and advantages will appear and be brought out more fully in the following specification considered with reference to the accompanying drawings throughout which like parts are designated by like numerals.

In the drawings:

Figure 1 is a front elevation view of a therapeutic machine embodying my invention.

Figure 2 is a separate view of one of the applicator electrodes.

Figure 3 is a view similar to Figure 2 showing a modified form of applicator electrode.

Figure 4 is a view of the human hand showing the method of application of the electrodes thereto.

Figure 5 is a perspective view of the structure of Figure 1, shown with the front panels and a portion of a side wall removed.

2

Figure 6 is a wiring diagram of the electrical circuits of the unit.

Referring more particularly to the drawings, I show an electrical unit comprising a transformer 10 having a primary winding 11 supplied through circuit wiring 12 and a plug 13 from a suitable source of alternating current, wiring 12 having a main switch 14 for controlling the operation of the transformer. Transformer 10 has a secondary winding 15 for supplying filament current to a rectifier tube 16, the transformer having a secondary winding 17 for providing the alternating current of proper voltage to be rectified by tube 16. Transformer 10 is also provided with a secondary winding 18 for supplying a low voltage for operating a pilot lamp 19 which indicates the operative condition of the transformer.

A conductor 20 is connected to the cathode of tube 16 for supplying the positive rectified voltage and current from winding 17, and a conductor 21 is provided for the negative voltage and current and is connected to a center tap of winding 17. A wave filter is provided and includes a choke coil 22 in conductor 20 and a pair of condensers 23 bridged across choke coil 22 and connected to conductor 21. A potentiometer 24 is connected across conductors 20 and 21 and is provided with a rheostat switch 25 and connected through a volt meter 26 to conductor 21.

Conductor 27 is connected to switch 25 and conducts the adjusted rectifier voltage and current from potentiometer 24 to terminals 28, 29 and 30 of switches 31, 33 and 32, switch 31 having a terminal 34, switch 32 having a terminal 35 and switch 33 having a terminal 36, the latter being all connected to a conductor 37.

I show resistors 38 and 39 connected between conductors 37 and 21, and one or more pairs of terminals 40 connected through a reversing switch 41, a resistor 42, and a milliammeter 43 across resistor 38.

A motor 44 is provided and through suitable worm gearing 44a and a cam 44b or the equivalent actuates switch 31 by an intermittent closing and opening action. Motor 44 is powered from the alternating current circuit 12 and is controlled by switch 14 and a selector switch 45 having a pair of motor control contacts 46 and a direct or galvanic current pair of contacts 47. Thus when switch 14 is closed the actuation of switch 45 to close contacts 46, thereby operating the motor, will cause contacts 47 to be closed, thus interconnecting the movable contact arms of switches 31 and 33.

Conductor 48 is connected to switch arm 33 and to the common bridged plates of a variable condenser 49, the complementary plates of which are severally connected to a condenser selector switch 50, the condenser 49 thereby having a steep range varying between .05 and 50 micro-

farads. Switch 50 has an "off" position 50a to permit operation with the galvanic current only. A pair of cables 51 are provided at one end with plugs 52 for connection to terminals 40 which may be of the jack type, respective cables 51 having respective electrodes 53, 54, at their respective other ends for application to the hand, arm, leg or other part of the body of a person to be treated.

The unit comprising my invention is suitably mounted in a cabinet or casing 55 having a suitable handle 56 for portability and having a front panel 57 on which the instruments and switches are mounted, which panel may be inclined, if desired, to permit easy manipulation of the switches and reading of the meter dials. A separate panel 58 may be provided for terminals 40, and ventilating louvers 59 may be provided in end walls 60 or elsewhere if desired. A suitable receptacle for an extension power cord plug and a fuse block may be provided in the rear wall of cabinet 55 as will be manifest.

The operation, purposes and objectives of my invention should be apparent from the foregoing description. Transformer 10 is energized by the plugging of plug 13 into a suitable socket connected to a source of alternating current and the closing of main switch 14. Transformer winding 15 supplies heater current to the filament of rectifier tube 16, and the power winding 17 of transformer 10 connected to the plates of tube 16 and conductors 20 and 21 provides a rectified alternating current which is now a pulsating full wave direct or galvanic current. The wave form of the current is smoothed out by the filter comprising choke coil 22 and filter condensers 23 and the resulting current is therefore a pure galvanic or direct current.

Assuming switch 33 is in the mid or "off" position, this galvanic current can be applied at any desired voltage, by the adjustment of potentiometer 24 and rheostat 25, to the electrodes 40 through conductor 37 by the closing of manual switch 32, the values of the voltage and current being read on voltmeter 26 and milliammeter 43 respectively.

Condenser 49 can be charged from the galvanic current manually by throwing switch 33 to switch terminal 29, it being seen that the current then flows through conductor 27, switch 33 and conductor 48 into condenser 49, the value of the charge being variably determined by the position of selector switch 50 connected to the various condenser units varying between .05 and 50 microfarads. Condenser 49 may now be manually discharged through the electrode circuit including terminals 40 by throwing switch 33 into contact with terminal 36 thereof.

When it is desired to apply a pulsating galvanic current to the electrodes and terminals 40, switch 33 is turned into off position, and motor 44 is started by the operation of selector switch 45 to closed position, which operation interconnects contacts 46 closing the motor circuit, and closing contacts 47 which connect condenser 49 through conductor 48 to the arm of switch 31. Motor 44 periodically moves switch arm 31 from contact 28 to contact 34, thus alternately charging the condenser and discharging it through the electrode circuit. It will therefore be seen that the electrode current is a direct rectified current having a superimposed condenser discharge current.

I have found by extensive use and numerous tests that this current is much less painful to a patient being treated than has been possible with the use of apparatus as heretofore known and constructed, being a smoother current and substantially free of alternating current ripple. Whenever delivery of rectified current to the electrodes is desired, switch 32 must be closed and manifestly, pulsating discharges from the condenser may, if desired, be delivered to the electrodes with or without the rectified current per se.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

Having thus described my invention, what I claim as new and desire to secure by Letters Patent is:

1. In a therapeutic machine, a source of alternating current, a full wave rectifier connected to said alternating current adapted to supply pulsating direct current, a filter in said pulsating direct current circuit, a bank of storage condensers connected in parallel having a selective switch adapted to selectively connect individual condensers, an electric motor connected to said original source of power, electrodes adapted to apply current to a patient being treated, and switching means adapted to selectively apply rectified currents or condenser discharge currents or rectified current and condenser discharge current to said electrodes, said electric motor being adapted to control said switching means to periodically connect and disconnect said switching means.
2. In a therapeutic machine, a source of electric power, a full wave rectifier connected to said source of power adapted to supply rectified current, a filter in said rectified current circuit, a potentiometer in said circuit, a plurality of condensers of varying capacities connected in parallel having a selective switch adapted to selectively connect individual condensers, an electric motor connected to said original source of power, electrodes adapted to apply current to a patient being treated, and switching means adapted to selectively connect said electrodes to said pulsating current or condenser discharge currents or rectified current and condenser discharge current, said electric motor being adapted to control said switching means to periodically connect and disconnect said switching means.

IRVING REHMAN.
